ELECTRODE

Ralph Cortese, Newark, N. J.

Original application May 17, 1945, Serial No. 594,226. Divided and this application August 5, 1947, Serial No. 766,145.

3 Claims. (Cl. 176—126)

1

This application is a division of my copending application, Serial No. 594,226, filed May 17, 1945, issued May 11, 1948, as U. S. Patent No. 2,441,260, and entitled Electrode, and the invention relates to fluorescent tube lighting, and similar space discharge equipment, and more particularly concerns an electrode construction for the cold cathode operation of fluorescent tubes.

Another object is to provide an electrode structure for space discharge tubes operating under cold cathode conditions, which structure contributes appreciably and without detrimental effect thereon, in the preliminary processing of the tubes by the internal bombardment method and which is capable of satisfactorily operating the tubes with high efficiencies at elevated current densities without appreciable increase in the electrode size over those heretofore customary in the art, and with, in the most part, no criticality attaching to the dimensions thereof, which minimizes cathode drop with substantial avoidance of long dark spots in the tube, so that substantially the entire length of the associated tube contributes to the production of useful light, wherein sputtering in large measure is avoided, and in the use of which electrode both striking and operating voltages are minimized.

Other objects and advantages in part will be obvious and in part pointed out hereinafter during the course of the following description, taken in the light of the accompanying drawings.

My invention accordingly resides in the several combinations of elements, features of construction, and association of parts, as well as in the relation of each of the same with one or more of the others, the scope of the application of all of which is more particularly pointed out in the claims at the end of this specification.

In the drawings wherein I disclose several embodiments of my invention,

Figure 1 comprises a fragmentary vertical view, partly in section and partly in elevation, disclosing the embodiment of my invention which I prefer at present,

Figures 2, 3 and 4 fragmentarily disclose in vertical elevation, transverse section of line 3—3 of Figure 2, and longitudinal section the details of a second embodiment of my invention; while

Figure 5 discloses in schematic illustration certain phenomena attendant upon the practice of my invention.

Figure 6 is a side elevation of a complete tube employing paired electrodes constructed according to the embodiment disclosed in Figure 1.

Like reference characters denote like parts in the several views.

To permit more ready and thorough understanding of my invention, it may be noted at this point that in comparatively recent years, somewhat revolutionary changes have occurred

in the illumination art. In large measure, the incandescent filamentary type of lamp is being rapidly replaced for a wide variety of uses by the fluorescent lamp.

Despite the high degree of refinement to which the incandescent lamp had heretofore been developed, its very nature, whereby it relies for its entire emission upon the production of intense heat, definitely limited the theoretical maximum efficiencies which could be achieved thereby.

The introduction of the fluorescent lamp permitted radical broadening of the possibilities available in illumination engineering. The almost complete energy conversion into the visible light spectrum with the substantial elimination of infra-red radiation in large measure removes the presence of sensible heat. Theoretical efficiencies are increased. Noteworthy flood-lighting now is available. Batteries of 2, 3 or 4 or more lamps can be arranged for desired lighting effects. Moreover, novel arrangements are available when two or more batteries of tubes are employed in combination. Effective color combinations can be achieved directly by selectively employing lamps coated on their interior walls with desired fluorescent salts or phosphors. Limitations in this respect are imposed almost entirely by the ingenuity of the operator.

It may be noted at this point that probably the basic limiting factor heretofore confronting the exploitation of fluorescent tube lighting equipment in the solution of illumination problems is the conception so prevailing in the art that hot cathode operation of the tubes was essential for the most advantageous results.

Under Claude's law, a cold cathode, without emissive coating, can carry only about 0.04 ampere of electric current per square inch of surface area, without detrimental overheating.

Through the simple expedient of coating the working surface of this electrode with electron-emitting coating, such as strontium or caesium oxide or the like, electron emission can be increased nearly ten fold, to about 0.3 to 0.4 ampere per square inch.

While these current densities are sufficient, in large measure, for normal operation of the tube in actual practice once the tube has been properly manufactured, the dual drawback is still found to exist that: 1. The tube electrodes must be too large and too long when substantial currents are carried, i. e.; large-sized tubes, and 2, the electrodes are detrimentally over-heated and will give rise to a sputtering deposit on the vitreous walls of the tube container during preliminary manufacture unless external heating equipment is employed.

An important object of my invention, therefore, is to provide a method of preliminarily processing fluorescent and like space discharge

tubes so as to avoid in substantial measure the many disadvantages and deficiencies of the prior art, and at the same time, to provide a technique whereby substantially all residual moisture and occluded gases are removed from the tube by the internal ionic bombardment method in the substantial absence of costly and space-consuming external auxiliaries, and in which the electrodes alone participate in the production of the required elevated temperatures, without, however, any appreciable increase of the electrode size over that heretofore prevailing, without appreciable damage to the electrode itself, and without sputtering of the electrode material on the wall of the tube, the electrode being fully capable of satisfactory and efficient operation during the subsequent normal use of the tube.

As a first step toward solving the many difficulties hereinbefore recited, I decided upon the expedient of placing an oxide coating on both the internal and external walls of the electrode rather than upon the interior surface alone, as has heretofore been the case. I anticipated a theoretical doubling of the effective current carrying capacity, with but little increase in temperature and with no increase in the physical dimensions of the electrode. In point of fact, superior results were actually achieved in practice. The current-carrying capacity was by no means doubled, but it was appreciably elevated. However, while satisfactory removal of moisture and occluded gases could be achieved, the temperature of the electrode was raised to such values that highly skilled operators were required in carrying out the manufacturing operation. Moreover, some sputtering in the region of the mouth of the electrode was likewise observed. It was apparent that more was required in order to produce entirely satisfactory results.

I thereupon conceived the expedient of providing an electric field in the region of each electrode, auxiliary to that maintaining between the electrodes themselves when the latter were subjected to alternating potentials, and asserting its presence between the electrodes and the adjacent walls of the tube container. Such field, properly designed, will effectively prevent the deposition of metal on the tube walls and at the same time will channel the electrons from the adjacent electrode, during the negative half-cycle of that electrode, toward the opposed electrode, thus resulting in the greatest possible ionization at maximum energy of the electrons.

I provided this field, in a first embodiment of the final form of my invention, by encircling the ordinary shell electrode by several turns of wire, which spiral anode was concentric with and spaced from the electrode by an amount sufficient for the field to assert itself. The number of turns of the anode wire was such, and the spacing therebetween, that is, the pitch distance, so selected, that the electrons could flow freely therebetween. When this spiral element was constructed so that its turns projected slightly beyond the open end of the adjacent electrode, in the direction of the opposed spaced electrode, I observed that it fulfilled admirably its function as an anode. By coating this anode with an electron-emissive salt, I found that it participated in the electron-emission function of the main electrode. By the use of such anode, I found that for the first time, the substantially increased current of the preliminary processing could be effectively carried by the electrode without damage to the latter and without detrimental sputtering and

deposition of sputtered metal on the walls of the tube.

And now having reference more particularly to that embodiment of my invention shown in Figures 2 through 4 of the drawings, the vitreous envelope 10, in the form of an elongated cylinder, has a re-entrant portion at each end thereof, terminating in an internal stem or press 11. Support wire 13 is mounted therein, fast to lead-in wire 17, and carries at its free end a cup-shaped or shell electrode 14, of conventional size and dimension. In the preferred instance, to illustrate, its length is of the same general order as its diameter, that is, it has no really definite major axis, other than that provided by the shell like contour. I provide an anode concentric with and disposed about the electrode 14 throughout its length comprised of several turns of wire 15. At least one turn of this wire projects beyond the outer edge of the electrode in the direction of the opposed electrode. In the preferred embodiment, the free end of this spiral 15 is connected to electrode 14 at point 16. The other end of the wire 15 is connected at 18 to the lead-in wire 16. Tubulation 12 serves for the evacuation of the tube 10.

To illustrate, it is desired, in order to compete effectively with the known hot cathode fluorescent tubes, to operate with a cup-shaped electrode having an internal developed area of approximately 1.2 square inches and an effective inner diameter of about $\frac{3}{8}$ of an inch. Such an electrode, capable of operating a 25 mm. diameter tube, must function satisfactorily at a current density of 0.36 ampere.

Ordinarily, it must be effective in carrying temporarily, and without detrimental overheating and without detrimental sputtering, a current ranging from about 2.0 to about 2.5 amperes during the preliminary processing of the tube.

Coating both the inside and the outside surface of the electrode with electron-emissive oxides, I found a partial solution of the problem confronting me was obtained in that proper current intensity could be achieved during normal operation at an electrode temperature ranging from about 500° C. to 600° C. However, as has hereinbefore been stated more generally, such electrodes could not be successfully employed in preliminary processing of the tube under bombardment, and some detrimental sputtering was observed to take place.

I thereupon constructed the spiral 15 as hereinbefore referred to. In the instance undergoing description, I imparted a diameter of about $\frac{1}{8}$ of an inch thereto, in that instance where a shell is employed at $\frac{3}{8}$ of an inch diameter, leaving a free space of about $\frac{3}{32}$ of an inch around the shell. Upon coating the wire as well as the shell and thereafter processing several tubes by the glass-heating-by-bombardment process, uniform results were achieved. I was able to raise the current in the tube to 2.5 amperes without undue risk. Upon shorting leads 16 and 17 (Figure 2) so that the shell 14 and wire 15 operate in parallel, I found that the entire shell assembly could be raised to the required temperature of 750° to 800° C., solely by way of internal bombardment without damage to the electrode construction.

I constructed the wire spiral 15 of pure iron, although nickel, molybdenum, or any other heat-resisting metal could be effectively employed. In the present instance, the wire has a diameter of 0.031 inch and the pitch distance is about $\frac{1}{8}$ of an inch. My observations have disclosed that

these dimensions are not critical and that the design of the electrode is not limited in the manner as is true of the construction of filamentary electrodes. Thus, a shell of 1.2 square inch internal area I find will work just as effectively with 0.3, 0.35 or 0.4 ampere current.

It has been explained hereinbefore how a tube electrode prepared in the manner just described will operate with a high degree of effectiveness in the preliminary manufacture of the tube. It will now be described how such an electrode operates effectively during the normal use of the tube after it has been sold and placed into operation. Here again, just as in the instance heretofore described, effective contrasts will be drawn between the prior art cold cathode tubes on the one hand and my new electrode construction on the other hand.

Assuming therefore that a shell electrode, properly oxide coated, and in a tube which has been properly heat treated, and assuming an inside emitting surface of said electrode of say 1.2 square inches, then assuming the shells to carry their load according to Claude's law to the maximum rate of 0.043 ampere per square inch, a total permissible amperage of 0.0516 ampere can be achieved. Long tube life will be achieved; and with a space of about 48 inches between the opposed electrodes, there will be about 320 volts drop across the electrodes when operating at alternate current after initially striking at a voltage in the region of about 550 to 600 volts. The energy output of such a tube is very low, ranging from 10 to 12 watts with a tube of 10-25 mm. diameter. That is, brilliancy is quite low. To obtain a high degree of illumination over a wide area a number of lamps must be strung together in series.

Increase in wattage consumption of the tubes is indicated as by passing greater current therethrough, thereby boosting the surface brilliancy, decreasing the operating voltage, and cutting down the operating costs. Thus, to illustrate, upon increase of the current from the 0.0516 value hereinbefore referred to, to say about 0.150 ampere, the lamp brilliancy will be appreciably greater, the operating voltage will drop to about 280 volts or thereabouts, and fewer lamps will be needed to maintain the same level of illumination.

When I surrounded this electrode with a few turns of pure iron wire, all as described heretofore in connection with spiral 15, and spaced the same from the shell 14 so as to provide enough space for the electrons to move rather freely around it, I achieved the results which I sought.

My observations were that the spiral 15 served as the anode of a sort of filamentary electrode when the last turn thereof was extended slightly beyond the end of the shell 14. By that I mean no sputtering occurs on the inside glass wall around the electrode. Moreover, I observed that no cathode glow occurred on the outside wall, this advantageous phenomenon being due in all probability to the electric field set up by the anode in phase with and of the same instantaneous polarity and potential as that of the shell 14. Thirdly, I observed that the anode emits electrons by field emission in appreciable quantity. In fact, at the initial stage of bombardment, the anode is made to supply the current that the cathode cannot supply. Thus, with ionic bombardment taking place inside the shell, I believe it to be a fair assumption that the 0.36 ampere

from the interior of the shell 14 and about 0.06 ampere from the exterior of the shell and from the anode. Finally, I observed no cathode glow to occur on or at the wire anode 15.

In this embodiment, and under these conditions of operating, I find the operating temperature of the shell such that this latter assumes a dull red color, indicating a temperature of about 600° C. While it is true that I operate my cathode shell at a substantially higher temperature than has heretofore been suggested according to Claude's law, this value nevertheless falls far short of the hot cathode operating temperature of from 1000° C. to 1200° C. This operating temperature, while sufficient to give rise to an appreciable field emission, is not sufficiently elevated to result in dangerous softening of the metal of the electrode. The field emission could be increased by winding the anode 15 with more turns of wire. I prefer, however, to provide sufficient space, say the approximately $\frac{1}{8}$ of an inch pitch distance already referred to between adverse turns of the wire, I having observed that in practice this distance is sufficient to prevent sputtering of the electrode material on the glass walls of the tube.

I have further observed that during the normal operation of the tube, the interior of the vitreous wall 10 becomes constantly charged to a negative potential, as indicated schematically in Figure 5. Now, shell 15 is alternately positive and negative during each half-cycle of the energizing current; when positive, the electric field created thereby attracts the electrons emitted by the electrode. During the negative half-cycle of the charging current, however, all the parts coming under the influence of the electric field of spiral 15 are attracted thereby, as are many ions created by the electron bombardment and thereupon coming into the influence of the field of electrode 14. It is the extreme mass of these ions which in large measure accounts for the sputtering which has heretofore been so detrimental.

Referring now to Figures 3 and 4, annular spaces $a-b$ and $c-d$ are established between shell 14 and wire 15, and between wire 15 and tube 10, respectively. When elements 14 and 15 are positive, then the region $a-b$ carries a positive charge. As a result thereof, it not only attracts electrons thereto, but at the same time either repulses the positive ions or at least serves as a brake therefor. This lowered momentum results in their being less destructive when they impact on the shell 14. Space $c-d$ is likewise charged positively at this time, and thus to a certain extent at least, attracts the negative charge from the glass wall 10. This has the effect of establishing what may be termed a screen or shield preventing in large part the positive ions from reaching the glass envelope and perhaps resulting in failure at local points.

Because of the positive field which is thus established around electrode 14 during the positive part of the energizing cycle, many of the migratory positive ions do not reach this electrode, while those which do bombard thereagainst have much less disruptive effect, due to their lowered velocity and hence diminished momentum.

Now when the elements 14 and 15 are negatively charged, a profusion of electrons escape from the interior of shell 14, while lesser quantities escape from both the exterior surface of shell 14 and from wire anode 15. It should be noted that elements 14 and 15 are simultaneously at the same negative charge. Accordingly, field

a—b becomes negatively charged so that a strong electric field of negative potential is formed around electrode 14. Those electrons which escape from region *a—b* progress to a large extent towards the opposed electrode, which normally is positive. These electrons carrying over from the field *a—b* form a negative shield around the column of electrons escaping from the open end of electrode 14, this screen contracting the pencil of electrons and shielding the outer edge of this electrode, so that no sputtering can occur at that point. Simultaneously, the region *c—d* becomes negatively charged so that most of the migratory positive ions are attracted and as well, a strong tendency exists to neutralize the charge of the glass surrounding the electrodes.

I have just described the manner in which the presence of the anode participates in the establishment of electric fields which during the positive half-cycle of current flow shields both the electrode and the adjoining region of the glass envelope from ionic bombardment, and which during the negative half-cycle of current flow effectively dissipates the negative charge from the tube walls and directs the pencil of electrons towards the opposed, positive electrode.

It will now be in order to discuss briefly the advantageous results attendant upon the operation of the shell electrode at comparatively high temperatures during the normal service of the tube. By operating the electrodes 14 and 15 at elevated temperatures which while substantially higher than those heretofore customary, being in the neighborhood of 500° to 600° C., it is insured that the metal will not be softened to a dangerous extent. Nevertheless, these temperatures are sufficiently high to reduce the work barrier or function of the emitting surface of the electrode so that a much larger quantity of electrons can be emitted from the electrode surface than has heretofore been possible under cold cathode operation. I accomplish this simply by bombarding the electrode by a combination of electrons and positive ions until electrode temperature is reached where the work barrier is substantially lowered and an electron emission is achieved with substantially less cathode drop than has heretofore been possible.

While the form of tube shown in Figures 2 through 4 proves initially satisfactory, I have found that some difficulty was encountered from time to time in connecting the shell 14 and the spiral 15 together at 16. To illustrate, upon undertaking to install my new electrode construction into a tube of 38 mm. diameter, then the space *c—d* (Figures 3 and 4) becomes much larger than in the case of tubes of 25 mm. diameter. The desirable field action is diminished greatly in such instance, due probably to the negative charge on tube 10 being too remote from spiral 15. In such instance, electron emission appears not only around spiral 15, but also around the interior and exterior of the shell 14. Inasmuch as the weld 16 serves only to support spiral 15 and to keep it in properly spaced relation to electrode 14, I find it convenient in certain instances to replace the wire shield 15 with a cylindrical anode 18 closely encircling shell electrode 14, being spaced therefrom to a slight extent as illustrated in Fig. 1.

I prefer to construct this ring anode 18 of thin sheet metal having a thickness of say 0.005 inch. It may, however, conveniently be made of closely wound wire or with closely woven metal sheeting. The plain sheet metal I find, however, to be quite

cheap to manufacture and to give entirely satisfactory results.

A support wire 19 carries ring 18 while support wire 13 carries electrode 14. These support wires 13 and 18 extend through press 11 and are connected with external lead-in wires 16, 17.

In experimenting with this new construction, I found that it was entirely unnecessary in order to obtain the desired avoidance of sputtering deposit on the glass tube 10 for the anode to extend the entire length of the cathode 14. Moreover, I established that the distance which I call "E," between the open end 14' of shell 14 and the inward edge 18' of cylinder 18 was critical at least to a certain extent. I found that this distance should vary between 0.2 to about 0.4 times the diameter of the ring 18 itself.

When so constructed, all the desirable results heretofore sought I found to be admirably achieved. To satisfy myself that such was the case, I took occasion to measure the current established between lead-in 16, 17 when lead-in 17 was connected to the source of power. I found that when a total of 350 milli-amperes current flowed through the electrode 14, then about 75 to 120 milli-amperes current was flowing through these two lead-ins. Inasmuch as this current was measurable with a direct current meter, this established that a uni-directional alternating current flow had been achieved through rectification in the mercury arc. Moreover, since at all times the lead-in 17 was positive with respect to lead-in 16, it is reasonable to assume that electrons flow from anode 18 through lead-in 16 to lead-in 17. Upon disconnecting lead-in 16 from lead-in 17, and thereupon measuring the potential difference therebetween, this was found to attain a value of from 25 to 60 volts, direct current. It appears to be a reasonable conclusion that this potential exists between the gas column and the anode 18. It may thus logically be concluded that the higher the operating current, the lower the voltage across the discharge gap, a phenomenon which is found to take place in actual practice.

Upon contrasting the operation of the construction according to Figure 1 with that according to Figures 2 through 4, inclusive, I concluded that while in the embodiment according to Figures 2 through 4, improved results are achieved if the spiral 15 is oxide coated, it is unnecessary in the embodiment, according to Figure 1, to coat the ring anode 18 with an oxide coating. Only the interior surface of the shell 14 need be coated for electron emission. I find that using the open stop-cook technique of manufacture, then with a ring anode having a width of $\frac{1}{4}$ an inch and a diameter of $\frac{1}{8}$ of an inch, and employing a shell of 1,259 inches developed surface arc, I can by internal ionic bombardment, properly heat a tube of 8-foot length and of 25 mm. diameter in very easy and rapid manner, with sensible reduction in manufacturing costs and with the production of a clean and long-lasting lamp.

The practice of my invention makes it readily possible, for the first time, to employ a shell type cathode of minimum dimensions with increased current carrying capacity under cold cathode operation. My new technique makes it entirely possible for the electrode to have an initial current-carrying capacity sufficient to heat both the surrounding glass envelope itself and the electrode by internal bombardment to a temperature sufficiently high to drive off retained moisture and occluded gases, while avoiding abnormal sputtering of the cathode material. I find that the heat

imparted to the shell surface by ionic bombardment increases the kinetic energy of the electrons in the cathode metal, thus freeing more electrons through a weakened potential energy barrier. Moreover, the cathode drop across the electrodes is appreciably diminished, while both the striking voltage and the operating voltage of the arc itself are substantially lowered. All these, along with many other highly practical advantages, attend upon the practice of my invention.

It may be noted that the phenomenon is observed that the working area, that is, the electron-emissive area, of my electrode is large during the initial bombardment process, but is therewith decreased during the normal operation of the electrode. This phenomenon is attendant upon the practice of my invention according to Figure 1, simply by coating only the interior surface of the shell 14. With such construction, then at the very outset of the preliminary bombardment the combination of the three factors comprising the excess of bombarding current, the high work function of the surface of the shell, and the elevated air pressure or gas pressure maintaining in the tube serve to spread the bombarding arc over the entire electrode assembly. This latter is brought to a dark cherry red temperature approximating 700° C. Thereupon, as the original coating of salts of electron-emissive substances is reduced to highly emissive oxides, the shell 14 progressively takes the current load until it attains a light cherry red temperature corresponding to about 850° C., and thereupon carries substantially the entire tube current, amounting to about 2.50 amperes. When this current levels off at a steady value, then the tube is ready to be cooled, filled and sealed off.

While, in general, the character of the salts employed are sufficiently oxidizable to assume excellent elimination of moisture and occluded gases I nevertheless find it advantageous in some instances to subject the electrodes, with their electron-emissive salt coatings, to a reducing treatment prior to assembly in the lamp. In this way I assure complete elimination of moisture and occluded gases in the subsequent operations wherein the electrodes are brought to a light cherry red heat.

Since many embodiments of my invention will readily occur to those skilled in the art, once the broad aspects thereof are disclosed, it will be understood that all matter described herein,

or shown in the accompanying drawings, is to be as illustrative and not in a limiting sense.

I claim as my invention:

- 5 1. As a new article of manufacture, a space discharge tube, comprising, in combination, a glass envelope, a shell electrode sealed therein in the form of a cylindrical cup with an open face and a closed bottom and having an electron-emitting oxide coating on the interior thereof, and a cooperating cylindrical ring anode also sealed therein and encircling said electrode in uniformly spaced relation thereto and extending therebeyond a slight distance.
- 10 2. As a new article of manufacture, a space discharge tube, comprising, in combination, a glass envelope, a shell electrode sealed therein in the form of a hollow cylindrical cup with open face and closed bottom, and a cooperating cylindrical ring anode also sealed therein and encircling said electrode in substantially uniformly spaced relation and extending therebeyond a slight distance, the space from the outer edge of the electrode to the inner edge of the ring anode being between approximately 0.2 and approximately 0.4 times the diameter of the anode.
- 15 3. As a new article of manufacture, a space discharge tube, comprising, in combination, an elongated glass envelope, a pair of cup-shaped electrodes with cylindrical walls and closed bottoms sealed therein at opposite ends thereof with the cupped openings facing each other, each electrode having an electron-emitting oxide coating on the interior thereof, and a corresponding pair of cooperating cylindrical ring anodes respectively
- 20 30 35 uniformly encircling said electrodes in the regions of their open ends only.

RALPH CORTESE.
